(57) **CLAIM**

The ornamental design for a fuel injector and electrical box of the fuel injector, as shown and described.

DESCRIPTION

FIG. 1 is a perspective view of a fuel injector and electrical box of the fuel injector showing our new design;

FIG. 2 is an elevational view of one end of the fuel injector and electrical box of the fuel injector shown in FIG. 1;

FIG. 3 is an elevational view of an opposite end of the fuel injector and electrical box of the fuel injector shown in FIG. 1;

FIG. 4 is an elevational view of one side of the fuel injector and electrical box of the fuel injector shown in FIG. 1;

FIG. 5 is an elevational view of an opposite side of the fuel injector and electrical box of the fuel injector shown in FIG. 1;

FIG. 6 is a plan view of a front of the fuel injector and electrical box of the fuel injector shown in FIG. 1; and,

FIG. 7 is a plan view of a back of the fuel injector and electrical box of the fuel injector shown in FIG. 1.

In the drawings, the broken lines depict environmental subject matter only and form no part of the claimed design. The fuel injector and electrical box of the fuel injector are shown with a symbolic break in the length of the fuel injector. The appearance of any portion of the articles between the break line forms no part of the claimed design.
